SELF-CONTAINED ESCAPE DEVICE FOR
SUBMERGED VESSELS

Charles W. Reed, Jr., Mobile, Ala.

Application June 24, 1941, Serial No. 399,521

3 Claims. (Cl. 114—16.7)

The improved escape device comprising the present invention is primarily adapted for use in connection with sea-going submarine vessels. The invention, however, is capable of other uses and the same may, with or without modification, be employed in connection with surface-cruising vessels for use in the event that such vessels become submerged.

Heretofore, considerable loss of life has occurred because of the inability of the crew of a submarine boat to escape from the vessel when the latter springs a leak while submerged or for any other reason fails to return to the surface of the water. The principal object of the present invention is to prevent such needless loss of life by providing an efficient and reliable means of escape for the crew of a submarine vessel under the conditions set forth above.

In carrying out the above mentioned object the invention contemplates the provision of a submarine lifeboat in the form of a watertight compartment mounted in the submarine or other vessel and releasable therefrom at will. The lifeboat or compartment is buoyant in the water and is provided with means whereby it may be entered by the submarine crew and then sealed for subsequent release and vertical movement through the water to the surface by virtue of its inherent buoyancy.

Another object of the invention is to provide an escape device of the character set forth above having mechanical means operable by the submarine crew from within the life saving compartment or operable by an outside rescue crew from a point exteriorly of the submarine and compartment for lifting the compartment out of the submarine and transfer of the crew to the surface of the water.

A still further object of the invention is to provide a mechanical lifting means for the submarine lifeboat which is extremely simple in its construction, consisting as it does of a system of gearing which is rugged and durable and which is, therefore, unlikely to get out of order.

Yet another object of the invention is to provide a mechanical lifting means for the lifeboat or compartment which is independently operable from one or more points or locations and which, when so operated, will serve to bodily and uniformly lift the compartment from the vessel without tilting the compartment, thereby eliminating the danger of the compartment binding against the sides of the cavity or recess in the vessel in which it is mounted.

Another object of the invention is to provide

a detachable submarine lifeboat or compartment which, when mounted in position in the submarine or other vessel for which it is intended does not materially alter the conventional marine design of the submarine nor in any way interfere with its normal operation or propulsion.

A still further object of the invention is to provide an anchoring means whereby the life saving compartment, although detachable and bodily movable away from the submarine vessel body is cable- or chain-anchored to the main submarine body in such a manner that when the compartment arrives at the surface of the water it will be retained in the vicinity of the submerged vessel to afford an indication of the position of the vessel for salvage purposes.

Other objects and advantages of the invention, not at this time enumerated, will become readily apparent as the following description, taken in conjunction with the accompanying drawings, ensues.

In the drawings:

Fig. 1 is a side elevational view of a submarine vessel constructed in accordance with the principles of the present invention showing the same afloat.

Fig. 2 is a top plan view of the vessel.

Fig. 3 is a side elevational view of the submerged vessel showing the life saving compartment released therefrom but anchored thereto and afloat.

Fig. 4 is a vertical longitudinal sectional view of the lifeboat or compartment per se.

Fig. 5 is a fragmentary sectional view taken substantially along the line 5—5 of Fig. 2.

Fig. 6 is a fragmentary sectional view showing certain details of the lifting mechanism.

Fig. 7 is a perspective view, diagrammatic in its representation of the lifting mechanism for the lifeboat.

In all of the above described views, like characters of reference are employed to designate like parts throughout.

Referring now to the drawings in detail, a submarine vessel is designated in its entirety at 10 and is of conventional construction except that it is formed with a cavity 12 in its body portion having a bottom wall 14, side walls 16, and front and rear walls 18. For illustrative purposes the cavity 12 is shown as being formed in the upper deck 20 of the vessel and substantially centrally thereof but it will be understood that the cavity may be at any desired point in the upper deck, either at the front, the rear or either side thereof, or in certain instances the

cavity may be formed in one of the side walls of the vessel.

Disposed within the cavity 12 is a box-like lifeboat or compartment 22 having a bottom 17, side walls 19, front and rear walls 21, and a top deck 23 provided with a lookout or observation tower 25. The compartment 22 is separable from the vessel and preferably has a slight clearance from the various walls of the cavity 12 in order to initially overcome any tendency for the compartment to become "frozen" therein due to unequal expansion of metal or due to suction. A plurality of vertical ribs 27 (Fig. 6) are formed on the side walls 19 exteriorly thereof and extend into guideways or grooves 29 formed in the side walls of the cavity 12. The ribs 27 and guideways 29 serve to prevent tilting of the compartment 22 relative to the cavity 12 in which it is mounted thus affording a still further safeguard against freeing or binding of the lifeboat in the recess.

The top deck 23 is provided with front and rear hatches 31 and 33 respectively, which are provided with sealing gaskets 35 and suitable fastening devices 37. These latter hatches afford means of egress for the crew from the lifeboat or compartment 22 when the latter is at the surface of the water. A hatch 37 establishes communication between the interior of the lifeboat and the tower 25.

The lifeboat or compartment 22 is air tight and is water tight and may be entered from the vessel proper through a pair of registering doors or hatches 24 and 28, the hatch 24 opening upwardly and inwardly of the compartment and being located in the floor or bottom 17 thereof and the hatch 28 being located in the bottom wall 14 of the cavity 12 and opening downwardly and inwardly of the body proper of the vessel 10. It is obvious that the hatches 24 and 28 need not necessarily be located in the bottom walls of the recess and compartment, but may be located in register in any of the side walls thereof if desired.

Suitable gaskets or the like shown at 30 serve to maintain the registering hatches 24 and 28 water-tight in order that intercommunication between the compartment and the body of the vessel proper may be had when the vessel is submerged. A series of spacing strips 32 formed of compressible material are disposed between the bottom wall of the recess 12 and the bottom of the lifeboat or compartment and are maintained under compression when the lifeboat is installed in position within the recess 12 for a purpose and in a manner that will appear presently. Suitable fastening devices 34 and 36 are provided for the hatches 24 and 28, respectively, for holding the same closed when deemed necessary.

Referring now to Figs. 4, 5, 6 and 7 wherein the lifeboat elevating means is best illustrated, the elevating means performs the dual function of lifting the lifeboat out of the recess or cavity 12 as well as serving to lock the same within the recess permanently until such time as an emergency requiring its release arrives.

A pair of bearing block members 50 and 52 are riveted or otherwise secured to the floor of the lifeboat interiorly thereof and adjacent the front and rear of the lifeboat at one side thereof. Each member includes a curved connecting arm 56 having bearings 58 and 60 formed at the ends thereof and extending at right angles to each other. Front and rear horizontal operating

shafts 62 and 64 extend through the respective bearings 60 and bridge the distance between the side walls 19 of the lifeboat and project through these walls and are journaled in the latter by means of suitable packing glands 66. The projecting ends of the shafts 62 and 64 have mounted thereon pinions 68 which mesh with toothed racks 70 which are disposed within recesses 72 formed in the side walls 16 of the cavity 12 and which extend vertically from points adjacent the bottom wall 14 to the upper edge of the cavity.

The disposition of the various pinions 68 and racks 70 is such that rotation of the shafts 62 and 64 in opposite directions will serve to cause the pinions to creep upwardly or downwardly as the case may be on the racks in order to elevate or lower the lifeboat from or into the cavity as required. Means is provided whereby this elevation or lowering of the lifeboat may be controlled by the crew of the submarine vessel from within the lifeboat or by a rescue crew operating exteriorly of the lifeboat and submarine.

Toward this end, a bevel gear 72 is mounted on each shaft 62 and 64 adjacent the inner end of the bearings 60 and each gear 72 meshes with a similar bevel gear 74. The gears 74 are carried at the front and rear ends respectively of a longitudinally extending operating shaft 76 which is journaled in the bearings 58.

The operating shaft 76 is provided with a ratchet wheel 78 in the medial regions thereof the peripheral teeth 80 of which are designed for cooperation with an operating pawl 82 carried by a tiltable oscillatable lever 84 which is journaled at 86 on the shaft 76. Manual oscillation of the lever 84 serves to rotate the shaft 76 in a clockwise direction as viewed in Fig. 5 in order that the shafts 64 will be rotated in such directions that the pinions 68 will move downwardly in unison on their respective racks 70. A locking pawl 88 serves to hold the shaft 76 against counter-clockwise rotation and thus, when the lifeboat has been lowered in this manner into the recess or cavity 12 the sealing gasket 30 and resilient strips 32 may be held under a positive degree of compression. When it is desired to rotate the shaft 76 in a counter-clockwise direction the pawl 88 may be moved to an inoperative position to release the ratchet wheel 78.

In order to elevate the lifeboat from the recess 12, a ratchet and pawl mechanism 90 which is similar in every respect to the mechanism just described except for its direction of positive stroke is mounted on the shaft 76 ahead of the former mechanism. A locking pawl 92 serves to prevent the force of gravity from returning the lifeboat to its normal position and thus the mechanism 80 functions as a manually operable jack whereby the lifeboat may be elevated from its cavity 22.

In order that the lifeboat may be elevated from the cavity 12 by an outside rescue crew operating from a point exteriorly of the submarine, an upwardly extending shaft 94, the lower end of which is journaled in a cage 96 carried by the shaft 76 is geared by means of cooperating bevel gears 98 and 100 to the shaft 76 and projects upwardly through the top deck 23 of the lifeboat and extends completely through the observation tower 25. The free end of the shaft 94 extends above the top of the tower and is squared as at 102 for reception of a jack handle or the like. A suitable packing gland 104 is provided at the top of the shaft 94 at the point

where this shaft projects through the top of the tower.

A portion of the shaft 94 is threaded as at 105 at a region where the shaft passes through the upper deck 23 of the lifeboat and is in threaded engagement with the boss 106 formed on the upper deck. By such an arrangement the entire shaft 94 and the gear 100 thereon may be elevated and disassociated from the operating shaft 76 when the latter is actuated by the crew from within the lifeboat. When the shaft 94 is employed for actuation of the lifting apparatus the threads 105 are allowed to run out of engagement with the threaded boss 106 in order that the shaft may be lowered to its fullest extent.

Referring now to Figs. 6 and 7, means is provided whereby the lifeboat may be anchored to the submarine body in order to prevent drifting of the former when the same is at the surface of the water. In this manner the lifeboat may serve as a buoy to give the approximate location of the sunken vessel. Toward this end a plurality of cables 106 are secured to suitable lugs 108 formed on the bearing members 52 and extend downwardly through small apertures 110 in the bottom wall or floor 17 of the lifeboat. The ends of these cables 106 are anchored to lugs 112 (Fig. 3) carried on the bottom wall 14 of the cavity 12. Obviously, if the crew of the lifeboat, upon reaching the surface of the water desire to cast away from the sunken vessel they may sever the cables 106 and seal the apertures 110 in any suitable manner.

It is believed that from the above description the nature and operation of the herein described submarine lifeboat will be clearly understood. The invention in its broadest aspect is concerned merely with the provision of a lifeboat for submarines which is embedded, so to speak, within the hull of the submarine vessel and which may be released therefrom when required. Obviously, in this lifeboat there may be installed such auxiliary equipment for the boat or for the members of the crew as is deemed expedient. For example, the lifeboat may contain oxygen tanks to sustain the crew. The tower 25 thereof may be provided with sighting apertures or even suitable armament if desired. The invention is not limited to the exact arrangement of parts shown in the accompanying drawings or described in the specification as various changes of detail in construction may be resorted to without departing from the spirit of the invention.

What is claimed is:

1. The combination with a submarine vessel having a sealed cavity formed in the upper deck

thereof, of a sealed buoyant lifeboat having a shell or hull portion removably disposed within said cavity, a plurality of vertically extending toothed racks secured to the side walls of said cavity and extending from points adjacent the bottom of the latter to points adjacent the rim thereof, a plurality of shafts extending horizontally through the side walls of the lifeboat hull, a pinion mounted on each shaft exteriorly of the hull and meshing with a respective rack, and means disposed within the lifeboat for rotating said pinions in unison.

2. The combination with a submarine vessel having a sealed cavity formed in the upper deck thereof, of a sealed buoyant lifeboat having a shell or hull portion removably disposed within said cavity, a pair of oppositely disposed vertically extending toothed racks secured to the opposite side walls of said cavity adjacent the forward end thereof and a similar pair of oppositely disposed vertically extending toothed racks secured to said side walls adjacent the rear end thereof, front and rear transverse horizontal shafts extending completely through the hull of the lifeboat and having their free ends projecting outwardly therefrom, a pinion on each of said free ends, and meshing with one of said racks, means connecting said shafts for rotation in unison, and a step-by-step operating device disposed within the lifeboat for rotating said shafts.

3. The combination with a submarine vessel having a sealed cavity formed in the upper deck thereof, of a sealed buoyant lifeboat having a shell or hull portion removably disposed within said cavity, said lifeboat having an upper deck lying in the plane of the upper deck of the submarine vessel and forming a substantial continuation thereof, a pair of oppositely disposed vertically extending toothed racks secured to the opposite side walls of said cavity adjacent the forward end thereof and a similar pair of oppositely disposed vertically extending toothed racks secured to said side walls adjacent the rear end thereof, front and rear transverse horizontal shafts extending completely through the hull of the lifeboat and having their free ends projecting outwardly therefrom, a pinion on each of said free ends, and meshing with one of said racks, a longitudinally extending shaft mounted for rotation within the lifeboat, gearing carried by said shafts and connecting the same for rotation in unison and a manually operable ratchet mechanism disposed within the lifeboat for rotating the longitudinally extending shaft in step-by-step fashion.

CHARLES W. REED, JR.
